US00D939799S

(12) **United States Design Patent** (10) **Patent No.:** **US D939,799 S**
(45) **Date of Patent:** **** Dec. 28, 2021**

(54) **BODY FOR CLEANER**

(71) Applicant: **Samsung Electronics Co., Ltd.**,
Suwon-si (KR)

(72) Inventor: **Jinsun Park**, Suwon-si (KR)

(73) Assignee: **Samsung Electronics Co., Ltd.**,
Suwon-si (KR)

(**) Term: **15 Years**

(21) Appl. No.: **29/781,965**

(22) Filed: **May 3, 2021**

(30) **Foreign Application Priority Data**

Dec. 15, 2020 (KR) 30-2020-0062201

(57) **CLAIM**

I claim the ornamental design for a body for cleaner, as shown and described.

DESCRIPTION

FIG. 1 is a front perspective view of a body for cleaner showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof, in accordance to an alternate configuration with the handle retracted;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the figures depict portions of the body for cleaner which form no part of the claimed design.
